(57) CLAIM

I claim the ornamental design for a stylized bill of a cap, as shown and described.

DESCRIPTION

FIG. 1 is a front perspective view of a stylized bill of a cap; FIG. 2 is a top plan view thereof;

FIG. 3 is a left side elevation view thereof; and,

FIG. 4 is a right side elevation view thereof.

The broken lines represent environmental structures that form no part of the claimed design.
